(57) CLAIM

The ornamental design for an item of clothing with attached towel and attached loop, as shown and described.

DESCRIPTION

FIG. 1 is a right side view of a first embodiment of an item of clothing with attached towel and attached loop showing our new design;

FIG. 2 is a front view of the first embodiment thereof;

FIG. 3 is a rear view of the first embodiment thereof;

FIG. 4 is a left side view of the first embodiment thereof;

FIG. 5 is a right side view of a second embodiment;

FIG. 6 is a front view of the second embodiment thereof;

FIG. 7 is a rear view of the second embodiment thereof;

FIG. 8 is a left side view of the second embodiment thereof;

FIG. 9 is a right side view of a third embodiment;

FIG. 10 is a front view of the third embodiment thereof;

FIG. 11 is a rear view of the third embodiment thereof; and,

FIG. 12 is a left side view of a third embodiment thereof. Top and bottom views not shown form no part of the claimed design.

1 Claim, 6 Drawing Sheets
